M. H. Betts,

UNITED STATES PATENT OFFICE.

MAJOR H. BETTS, OF BLOOMFIELD, NEW JERSEY.

CIGARETTE-BOX.

1,210,888.

Specification of Letters Patent. Patented Jan. 2, 1917.

Application filed October 12, 1915. Serial No. 55,722.

To all whom it may concern:

Be it known that I, MAJOR H. BETTS, a citizen of the United States, residing at Bloomfield, in the county of Essex and State of New Jersey, have invented new and useful Improvements in Cigarette-Boxes, of which the following is a specification.

This invention relates to cigarette boxes or the like, and has for its principal object the provision of a receptacle of this character which will be so designed that the cigarettes may be singly projected therefrom to a position where they may be readily removed without necessitating the opening of the closing flap.

A still further object of the invention resides in the provision of a device of the kind mentioned which may be stamped from a single blank of material, thus reducing the cost of the manufacture of the article to a minimum.

A further object of the invention resides in the provision of means for effecting a single delivery of the cigarettes from the package, and the formation of such means, whereby it may be normally sealed by the revenue stamp so that during the process of arranging the package for the discharge of the contents thereof, the revenue stamp will be properly mutilated and destroyed.

In the drawings: Figure 1 is a perspective view of the box showing the same in its normal sealed condition. Fig. 2 is a similar view showing the device operatively arranged for the single delivery of the cigarettes. Fig. 3 is a plan view of the blank. Fig. 4 is a plan view showing the box collapsed or folded.

The box is formed of a single blank of material such as illustrated in Fig. 1, the said blank being stamped so as to form relatively broad side walls 1 and 2, and end walls 3 and 4. The blank is scored or weakened along the parallel lines *b*—*b* so as to permit the material to be folded so that the wall 3 may be extended at right angles to the walls 1 and 2 when the box is set up. The wall 4 is formed as a continuation of the wall 2, being located at the normal free end thereof, and as shown, the material is scored along the lines *c*—*c* so that the mentioned wall 4 may also be folded to lie at right angles to the walls 1 and 2. Extended from the wall 4 is a securing tab 5 provided at one side with an adhesive 6 which

may be moistened and secured to the inner face of the wall 1.

Along one of the longitudinal edges of the wall 1 is an extension of the material from which the blank is formed which is designed respectively to form a wall 7 for the receptacle and a closing flap 8. Along the opposite edge of the wall 1, the material is provided with an extension subdivided into another wall forming portion 9 and a sealing flap 10. This extension is scored along the parallel lines *d*—*d* so that the flap 10 may be respectively flexed and extended into and out of the package, as will be understood. However, and in view of the purpose of the invention there is no necessity of ever moving the flap 10 out of the package after the cigarettes are placed therein, and it may, therefore, be desired to permanently secure said flap 10 to the wall 7. Aside from scoring or weakening the last mentioned extension along the lines *d*—*d* the wall forming portion 9 is slit along the parallel lines 11—11, the slits being extended in the same general direction as the weakened or mentioned scored portions *d*—*d* so that the intervening material between the slits is adapted to form a relatively flexible tongue 12 having its extremity 13 extended to a point beyond one side of the package, as shown in Fig. 1.

As stated, the primary object of the present invention is to provide a means, whereby, the cigarettes that are contained within the package may be singly discharged or at least projected, for a sufficient distance from the package to permit the same to be very conveniently withdrawn by the user as the occasion may demand. The width of the package or box is approximately equal to the diameter of the cigarette contained there-within. This is preferred in order that the cigarettes may very uniformly gravitate in the direction of the discharge end of the package, by simply canting the package. Aside from furnishing a means to permit the cigarettes to be singly discharged or projected to a discharge position, it is a secondary object to provide means which will prevent the original contents of the package to be removed and an inferior article or brand substituted therefor. It is now stated that in order to bring about this object the revenue stamp, such as shown at B in the drawings, 110

is adapted to be secured to the respective sides of the package or to the walls 1 and 2 thereof, while the connecting portion C of said stamp is adapted to be extended over the flexible tongue 12, the end 13 of the latter being extended to a manipulating distance beyond the portion C in order that it may be grasped between the fingers of the hand, and the stamp B destroyed, in 5 the act of pulling in an outward direction upon the portion 13. In this manner the stamp is not only destroyed but the flexible discharge tongue 12 is rendered loose or free, so that it may be flexed to the position 10 shown in Fig. 2.

After, you might say, ripping the stamp C to free the tongue 12, the entire package is canted so that the tongue 12 is disposed at the bottom of the package as illustrated 15 in Fig. 2. The package is then held in one hand of the user and by suddenly tapping the same against the other hand of the user or some relatively fixed object, the cigarettes will be forced under the impact of 20 striking the package against the tongue 12 and the latter flexed to the discharge position shown in Fig. 2, so that at least one cigarette will be projected to a position 25 where it may be conveniently grasped between the fingers of the hand of the user, and removed from the package. After removing a single cigarette from the package 30 the tongue 13 may of its own inherent resiliency, assume a substantially normal condition so as to prevent any accidental discharge of the contents of the package. It 35 may also be described that should the oper-

ator or user of the package wish to positively insure himself against any accidental discharge of the cigarettes from the package, he may manually press the tongue 12 to a point where its sides will frictionally come against the inner surfaces of the walls 1 and 2. The tongue 12 is then very securely held against accidental opening, as 40 45 will be understood.

The wall 7 and the flap 8 thereof are held permanently sealed against the package by a stamp D of the kind which is commonly used to designate the factory license of the 50 manufacturer of the cigarettes.

What is claimed as new is:

A single delivery cigarette box provided with a discharge opening and also having a wall near one corner of the receptacle, 55 provided with a relatively flexible tongue for closing the discharge opening and adapted to be flexed under the impact of a cigarette thereagainst when the package is struck against a fixed object, destructible 60 means for normally holding the tongue in a closed and inactive position, and a straight extension formed on the tongue in a plane therewith and projecting beyond the adjacent side of the package and serving as 65 a manipulating means for the tongue, whereby the tongue may be initially raised to destroy said destructible means.

In testimony whereof I affix my signature in presence of two witnesses.

MAJOR H. BETTS.
